[57] CLAIM

The ornamental design for an electronic camera with a screen, as shown and described.

DESCRIPTION

FIG. 1 is a top, front and right perspective view of an electronic camera with a screen showing my new design; FIG. 2 is a top plan view thereof; FIG. 3 is a left side elevational view thereof; FIG. 4 is a front elevational view thereof; FIG. 5 is a bottom plan view thereof; FIG. 6 is a right side elevational view thereof; FIG. 7 is a rear elevational view thereof; and, FIG. 8 is a bottom, front and left side perspective view thereof, wherein the cover portion is in an open position. The broken lines are shown for illustrative purposes only and form no part of the claimed design.
